UNITED STATES PATENT OFFICE.

JAN SZCZEPANIK, OF VIENNA, AUSTRIA-HUNGARY, ASSIGNOR TO SOCIÉTÉ DES INVENTIONS JAN SZCZEPANIK & CIE., OF VIENNA, AUSTRIA-HUNGARY, A FIRM.

METHOD OF PRODUCING WEAVING-DIAGRAMS.

SPECIFICATION forming part of Letters Patent No. 703,850, dated July 1, 1902.

Application filed March 19, 1900. Serial No. 9,330. (No specimens.)

To all whom it may concern:

Be it known that I, JAN SZCZEPANIK, a subject of the Emperor of Austria-Hungary, residing at Vienna, in the Province of Lower Austria, in the Empire of Austria-Hungary, have invented certain new and useful Improvements in Methods of Producing Weaving-Diagrams; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

My invention relates to the improvements in the method of producing diagrams, designs, or cards for weaving purposes by means of photography in a simpler and easier manner than heretofore performed and designed to be used directly in a suitable machine. According to this method I first of all produce a number of negatives or diapositives of the object of which the weaving diagram, design, or card is to be made and ultimately woven in a suitable loom to reproduce the figure. Each of these diapositives or negatives contains only those portions of the design to be reproduced that are to have the same thread-crossing or weaving-stitch. All other parts of the negative or diapositive are blocked or spotted out with a suitable opaque material, so that all the negatives or diapositives when combined will unite to form the whole design that is represented by the original negative or diapositive before it has been altered for this purpose. Each diapositive, suitably blocked out, is combined with the suitable binding-plate or combination of binding-plates placed in front of or behind the corresponding negative or diapositive, so that the projected image from each diapositive will be represented by a series of suitably-arranged black spots, which image is projected on the perforated plate or its equivalent, as one such made by photographic means. The light which passes through the illuminated perforations of this plate to a sensitized medium indicates a completed image, which is

an assemblage of all the plates projected, each plate being represented by its respective weaving-stitch.

For the purpose of this specification the negative or diapositive or other transparency, whether photographically made or otherwise, will be hereinafter designated as "slides."

In order that the invention may be properly understood, reference will be made to the accompanying drawings, in which like parts are similarly designated, and in which—

Figure 1 is a diagrammatic view in section showing an arrangement for projecting two images. Fig. 2 represents a slide of a flower the design of which is to be indicated in three different thread-crossings. Figs. 3, 4, and 5 indicate the separate slides to be used for producing the composite image indicated on the plate in Fig. 2. Fig. 6 shows an arrangement for combining three images simultaneously upon the screen. Fig. 7 is a section taken on the line A B of Fig. 6, showing a three-face reflector. Fig. 8 shows a portion of the perforated plate *i*. Fig. 9 shows a reflector having three reflecting-faces; Fig. 10, a similar one having four reflecting-faces.

Referring to Fig. 1, *a* is a front wall of a suitable dark room or chamber, in which is inserted an objective lens *b* at a suitable diaphragm-opening, and in front of this is arranged the device for reflecting through and uniting behind the lens two or more images on a screen. This device, as shown in Fig. 1, comprises two reflectors or mirrors *c d*, placed at an angle to one another and against the diaphragm-opening in the wall *a*, and arranged to reflect light from each of them through the lens, which is common to all the reflectors, and receiving the reflected light from each of them. Suitably located with relation to each of the mirrors *c d* are other reflectors or mirrors *e f*, which receive light passed through the slides *n* and the screens held in the frame *g*. It is of course obvious that these second reflectors or mirrors *e f* can be dispensed with when the source of light is placed opposite those *c d*, when the slides would have to be held in different frames, also opposite each; but the present arrange-

ment is preferred in order to facilitate manipulation. Beyond these slides are suitable collectors *h*, arranged to throw light from a suitable source (here shown as an arc-light) 5 through each slide and its screen or screens.

Within the dark room is a suitable stand *j*, which holds the perforated plate *i*, a focusing-screen *k*, and a sensitive medium *j*. Adjacent each slide *n* is one or more screens *l*, 10 held in the frame *g* with the slide, so that light can pass through both. These screens *l* are placed in either side of the slide or both when the exigencies of the case so require or demand and are of substantially the same 15 size as the slides and provided with series of spots arranged to indicate a weaving crossing, stitch, or pattern. Two or more of such screens may be used simultaneously, whose combined result will indicate a different crossing 20 than any of them taken alone, in which case they are disposed on either or both sides of the slide.

Referring to Fig. 2, which represents a suitable slide of a flower design to be woven 25 in three different thread-crossings and of which the design or cards are to be made, since the whole design is to contain three weaving-strokes, one in each of the parts indicated in the transparent portions 1, 2, and 30 3, three such slides (represented in Fig. 2) are made, and all those portions not to contain the same thread-crossing are spotted or cut out by a suitable opaque or mask. Each portion of the object on the slide when combined 35 with its respective screen will modify or change the distribution of light passed through it for the purpose herein mentioned. Thus it will be seen that if a slide such as shown in Fig. 3, in which the portions 1 representing the flower are transparent, be placed 40 in one part of this frame, for example, so that light will pass through it to the reflector *e*, and that another plate (shown in Fig. 4) containing the leaves which will be translucent, as indicated at 2, be placed so that light will strike the mirror *f* these two parts will be projected simultaneously upon the sensitive medium *j*. Now if a suitable screen to indicate a weaving-stitch—for example, a satin-crossing—be 45 placed in front or behind the flowers 1 and another screen arranged to indicate, for instance, taffeta be similarly used in conjunction with the plate represented in Fig. 2 the representation of the portions 1 and 2 on the 50 sensitized medium will thus indicate these respective crossings. Now if the plates be removed and the light cut off from, say, the lower one, and the plate (indicated in Fig. 5) in which the stems 3 are translucent be placed 55 in the upper part of frame *g* in Fig. 1, and the screen indicating twill-crossing be placed in front of it, then light be projected through both screen and plate these stems will be indicated on the sensitive film with twill-cross- 60 ings and the other portions of the medium, which have already been exposed, being unil-

luminated, will not be affected by the light, as is well known.

For simultaneously projecting three partial images upon the screen an apparatus, such as 70 shown in Figs. 6, 7, and 9, is used, in which *k* is a ground glass or other focusing screen capable of being replaced by the sensitive medium *j*; *i*, the perforated plate within the dark chamber between the lens and sensitive medium; *a*, the front wall of the chamber; *b*, the objective or lens in an opening in said wall; *d*, the combination of mirrors or reflectors, (shown in Fig. 9,) having reflecting-faces *c*, *d*, and *e*, being formed as a regular pyramid, in which the axis of the solid angle is in the line of collimation of the objective *b*. 75

In a suitable casing *s*, which carries the series of reflectors, are lenses arranged to 85 focus light on the reflecting-faces *c* *d* *d'*, and opposite each lens is a mirror or reflector *e*, *f*, and *f'*, and opposite this system of mirrors or reflectors is the frame *g*, carrying the slides 90 *n* and the screens *l*, a slide and a screen opposite each mirror, and opposite these slides suitable sources of light and collectors *h*.

Fig. 10 shows an arrangement of mirrors in which there are four reflecting-faces *c*, *d*, 95 *c'*, and *d'*, and it suffices to say that any number of pictures or partial pictures can be combined by arranging a corresponding number of reflectors, placed at an angle to one another, each reflector to receive light from a slide in the same manner as described in Figs. 100 1 and 6.

Fig. 8 shows the perforated plate *i*, in which the holes in the plate are indicated by 11.

I have heretofore employed for the production of such diagrams a perforated plate, 105 the perforations in which act as a series of pin-hole cameras, in which certain holes are cut out by means of a cover-plate in order to leave open such holes only as will produce the required thread-crossing, and it is 110 obvious that in order to do this these plates must be substantially as large as the perforated plate *i* and practically as large as the diagram produced. Now in lieu of employing plates of this size in order to cover up the 115 openings in the perforated plate I use plates or screens provided with black spots, each spot acting when projected to cut out the illumination of certain perforations in the plate *i*, thereby indicating the required thread-crossing. Said screens are of a size corresponding to the slide *n* used in the projection. Thus when combined with the slide these screens, which contain the black spot, will cause unilluminated portions in the projected 125 image, which unilluminated portions are arranged to fall on perforations in the screen *l*, will not illuminate said perforations, and thus cause no photographic record to be made. Such screens instead of being composed of 130 opaque spots on a glass plate can be made as a grating of lines ruled on such, and when

two such gratings are placed at an angle to one another, preferably but not necessarily at right angles to one another, the same result will be attained, such lines of course being of different translucency.

5 All the screens *l*, Figs. 1 and 7, must of course be accurately adjusted, so that when they are projected on the perforated plate *i* and sensitized medium *j* they will register with the required perforations *ll* that are to be covered. However, since all of the thread-crossing portions can be seen simultaneously on the ground-glass screen any defects arising from the bad fastening of these plates in position in the frame *g* can be readily corrected and register obtained. Now it is obvious that these thread-crossing plates *l* will have their black spots registering with the openings in the perforated plate *i* only in case of particular enlargement, and this enlargement must always be maintained, while at the same time it is necessary to keep the distance of the perforated plate from the objective *b*, the distance of the screen or the paper from the perforated plate and the distance of the optical apparatus from the frame *g* constant or fixed.

10 The entire design shown in Fig. 2 will now be reproduced upon the sensitized medium united, the flowers or blossoms *1* indicated in satin thread-crossings, those of the leaves in taffeta, and the stems in twill. If a diaphragm has been used with square holes in it, then these crossings will be indicated in the customary manner as squares, as each illuminated pin-hole produces an image of the diaphragm-opening. To facilitate the reading of the diaphragm when such is desired for a card-punching machine, these 15 different crossings can easily have a different outline—such as triangular, circular, cross-shaped, or any other desirable indication—by using such shaped diaphragms at the lens-opening.

20 45 The avoidance of adjustment very materially simplifies the apparatus; but, however, different objects are woven in different sizes. Hence the slides which serve for diagram-making must be taken of such a size that they 50 will give the required fixed enlargement. Such accurate photography can be produced now with the greatest ease by means of well-known photographic apparatus. It is also evident that a picture can be divided in as 55 many portions as desired and all the portions simultaneously projected upon the screen with their respective thread-crossing, it simply being necessary to arrange suitable numbers of reflecting-mirrors corresponding to 60 the numbers of portions to be combined, in the manner illustrated in Figs. 1 and 7.

Having thus described my invention, what I claim as new therein, and desire to secure by Letters Patent, is—

65 1. The method of producing an image to indicate weaving crossings or stitches, which consists in transmitting light from separate

70 portions of an object, each modified to indicate a weaving-crossing, through a lens common to all the images onto a sensitized medium, substantially as described.

2. The method of producing an image to indicate weaving crossings or stitches, which consists in simultaneously transmitting light from separate portions of an object each 75 modified to indicate a weaving-crossing, through a lens common to all the images onto a sensitized medium, substantially as described.

3. The method of producing an image to indicate weaving crossings or stitches, which consists in forming a slide of each part of the object, modifying each slide to indicate a weaving-stitch and reflecting light therefrom through a lens common to all the parts onto a 85 sensitized medium, substantially as described.

4. The method of producing an image modified in its parts to indicate weaving-crossings, which consists in forming a slide of each part, and projecting each part through ruled 90 screens, then reflecting the light therefrom through a lens common to all the parts onto a sensitized medium, substantially as described.

5. The method of producing a composite modified image, which consists in reflecting 95 the light from separate parts of the object through a screen indicating a weaving-crossing for each part and a lens common to all the parts onto a sensitized medium, substantially as described.

100 6. The method of producing weaving-patterns, which consists in reflecting light from separate parts of the object, each modified to indicate a weaving-crossing through a lens common to all the parts and then through 105 a screen onto a sensitized medium, substantially as described.

7. The method of producing weaving-patterns, which consists in reflecting separate parts of the object modified to indicate weaving-crossings through a lens common to all the parts and a perforated plate, whereby each part of the image is broken up into a number of light parts corresponding to the 110 number of holes of the perforated plate illuminated and projected onto a sensitized medium and thereby indicating a weaving-crossing in each part of the image and varying the outline of the light parts of the image by a suitably-shaped diaphragm, substantially as 115 described.

8. The method of producing an image modified in its parts to represent weaving-crossings, which consists in reflecting light from separate portions of the object, each modified 125 to indicate a weaving-crossing from a reflector, through a lens arranged to receive the reflected light from each portion and project it onto a sensitized medium, substantially as described.

130 9. The method of producing an image modified in its parts, each part broken up into points and the points in each differently grouped, which consists in reflecting light from suit-

able slides of the object to separate reflectors, thence through a lens arranged to combine all the images onto a sensitized medium, substantially as described.

5 10. The method of producing an image modified in its parts, which consists in forming transparencies of the corresponding parts of the object, passing light through said transparencies and screens, reflecting the light thus 10 modified from a reflector, thence through a lens arranged to combine all the images, and a perforated plate onto a sensitized medium, substantially as described.

11. The method of producing weaving-diagrams, which consists in forming a transparency of parts of the object, combining said transparencies with loom-stitch or crossing-indicating devices, reflecting the light passed through the combination, through a lens arranged 20 to combine the images and then through a perforated plate onto a sensitized medium and varying the outline of the separate images of the crossing-indicating parts of the image thus formed, by suitable diaphragms, substantially as described.

12. The method of producing weaving-diagrams, which consists in forming a transparency of parts of the object, combining said transparencies with loom-stitch-indicating gratings, reflecting light passed through the combination, through a lens arranged to combine the images and then through a perforated plate onto a sensitized medium, thereby producing the design-indicating thread-crossing and determining the outline of the thread-crossing indications by a suitably-shaped diaphragm, substantially as described.

13. The method of producing weaving-diagrams, which consists in forming a transparency of parts of the design to be woven, combining each transparency with a suitable screen, passing light through the combinations, reflecting light through them on reflectors, thence through a lens arranged to combine all of the images and then through a perforated plate onto a sensitized medium, whereby each image of the transparencies is disintegrated to indicate weaving-crossing and determining the outlines indicating the weaving-crossings by suitable diaphrams, substantially as described.

14. The method of producing weaving-diagrams, which consists in forming photographic transparencies of the object to be represented in the design, each transparency consisting of those parts to be indicated by the same thread-crossing, combining with each transparency

a suitable screen to indicate the respective thread-crossing, passing light through the combinations thus formed, through a lens arranged to combine images thereof and a screen or perforated plate beyond said lens onto a sensitized medium, the first-mentioned screens arranged to cause their opaque portions to render certain perforations in the perforated plate unilluminated and varying the outline of the projections through the illuminated apertures by the form of diaphragm-opening used, substantially as described.

15. The method of producing weaving-diagrams, which consists in forming transparencies of the object to be represented in the design, each transparency consisting of those parts to be indicated by the same thread-crossing, combining with each transparency a suitable screen to indicate the required thread-crossing, simultaneously passing light through the combinations thus formed and a lens arranged to combine images thereof, and a screen or perforated plate beyond said lens onto a sensitized medium, the screens and perforated plate being in fixed relation and proportion to each other, whereby the opaque portions of the screens will render certain perforations in the plate unilluminated, substantially as described.

16. The method of producing weaving-diagrams, which consists in forming transparencies of the object to be represented in the design, each transparency consisting of those parts to be indicated by the same thread-crossing, combining with each transparency means to indicate the required thread-crossing, simultaneously passing light through the combinations thus formed to reflectors, and passing the reflected images through a lens common to all of them and a perforated plate onto a sensitized medium, the said screens and perforated plate being in fixed relation and proportion to each other, whereby the opaque portions of the screens will render certain perforations in the plate unilluminated and varying the outline of the projections through the illuminated perforations by the form of the diaphragm-opening, substantially as described.

In testimony that I claim the foregoing as my invention I have signed my name in presence of two subscribing witnesses.

JAN SZCZEPANIK.
